MULTIPLE-RANGE SOUND-TRANSMITTING SYSTEM.

Application filed May 14, 1923. Serial No. 638,836.

My invention is illustrated in the accompanying drawings, in which

Figure 1 represents a system of resonance curves; and

5 Figure 2 shows diagrammatically one of the numerous forms in which my invention may be reduced to practice.

10 The range of sound frequencies which is covered by human speech and by music is so large that a sound receiving and sound radiating instrument, in order to operate satisfactorily, is required to transmit with uniform quality frequencies at least within the range of 500 to 3000 per second. If it 15 is desired to use a single sound responsive device at the sound receiving or sound transmitting end which is tuned and constructed so that it covers this entire range with fair uniformity, a damping would be required which is much greater than unity and which, 20 therefore, can be produced only to a very small extent by radiation damping, even if such a tuned system constitutes a coupled two- or three-wave system. In systems used 25 in the present day practice, the radiation damping amounts to only about 0.1 to 0.2. Therefore, very large friction damping must be employed in order to make such instruments fairly responsive to all frequencies 30 within the transmission range.

At the present day, in order to cover a large range of tone frequencies with one single instrument (either at the sound receiving or sound transmitting side of the 35 system) it is therefore possible to build such apparatus, such as microphones or telephones, only with a very large friction damping, which is for instance produced by mounting the diaphragm between rubber 40 cushions so that it becomes imperfectly fastened. Therefore, the large damping which must be inherent to these instruments in order to cover the entire range of tone frequencies is not produced to a sufficient extent by radiation damping, and therefore, is 45 produced at the expense of efficiency.

The above statements furnish an explanation why at the present day so many comparatively crudely designed and built instruments appear to give such comparative 50 good acoustic effects. Such instruments, for instance owing to the imperfect fastening of the diaphragm as explained above, have a great friction damping of their diaphragms 55 and reproduce all tone frequencies compara-

tively good but at a very low efficiency, that is to say, they have a very small sound intensity.

Most acoustic devices for the purpose of sound reception and sound emission, such 60 as microphones and telephones, employ diaphragms, practically all of which have, aside from their fundamental frequency, also overtone frequencies. By this characteristic feature the effect is automatically obtained 65 that these diaphragms cover a comparatively large portion of the entire tone frequency range and that they have a comparatively good effect at a great many points of their surface, namely, at those points where the 70 overtone frequencies are located.

I have attempted—and I am aware that others have made similar attempts—to construct the diaphragm such that a definite 75 pre-arranged group of overtones is formed and I have coupled such a diaphragm with correspondingly tuned air chambers in order to obtain a good efficiency at all of these overtone frequencies.

Of course, a good efficiency of such a device will be obtained only in case the equation exists for the sound receiver (microphone): radiation damping (d_{rad}) approximately=useful damping (d_{usef}), or more correctly expressed: $d_{rad} + d_{frict} = d_{usef}$. 80

In case of a sound radiator (telephone or loud speaker) the equation must exist: radiation damping larger than or at least not too small compared with the remaining (friction) damping. 90

Of course, sound transmitting devices of this characteristic can be built, but it is extremely difficult to properly arrange even only two or three of such frequency groups exactly as required, since in the construction 95 of such a device extremely careful workmanship and experimenting with each individual diaphragm is required. For this reason it becomes almost impossible to commercially manufacture such devices in quantities. Of course, even if three of such frequencies were 100 grouped together with the greatest care, the necessarily large range of tone frequencies, ordinarily used, would hardly be covered.

I am aware that at the present day sound 105 responsive devices of the above character have been constructed, which have good efficiency, but which cover only a comparatively small range of frequencies. So far as I know a range of frequency in the proportion of 1:2 110

(for instance 1000/sec.-2000/sec.) has been thus covered at a fairly good efficiency.

The present invention proposes to solve the problem of constructing sound apparatus, having a good efficiency throughout the entire tone frequency range commonly used, by using such sound receivers (microphones or the like) and sound radiators (telephones or the like) correctly built as previously mentioned, that is to say, constructed so that they have good efficiency within the comparatively small range for which they are designed. Accordingly the sound senders (telephones) which I propose to employ would have a radiation damping large or at least comparable with the remaining damping (friction damping) and the sound receivers (microphones) would have a useful damping equal to or at least comparable with the radiation damping + friction damping.

In case of acoustically coupled systems in addition to the proper selection of damping also the coefficient of coupling between the several systems must be properly selected. One must then, in case of sound receivers, tend to obtain the result that the energy transmitted from the radiating system (diaphragm) to the system coupled with it, constitutes an amount sufficient—for good efficiency—compared with the energy radiated by the radiating system (diaphragm). In case of sound senders the radiated energy (in the form of sound) must be large or at least comparable to the energy otherwise consumed in the coupled systems (for instance friction damping).

Since such instruments individually cover a comparatively small range of tone frequencies I attain the necessary large range for transmitting speech or music by using a plurality of such correctly constructed sound receivers and sound radiators each being tuned for a different band of frequencies. For example, one sound receiver may have at good efficiency a range from 600 to 1200 periods, the next from 1200 to 2400 periods and so forth.

It is obvious that the final result will be the better the more of such differently tuned systems of good efficiency are used.

I have shown in Figure 1 of the drawings three resonance curves I, II and III each representing the curve of a coupled system (acoustically coupled). In this case each individual portion of the coupled system is tuned to the frequency n_r which results in the two frequencies of the coupled system n_1 and n_2 . If a number of such coupled systems, each having a frequency range different from the others, are added and combined into one receiver or sender apparatus, the result will be a range of frequencies substantially covering the entire tone frequency range and in which at substantially all points of the range

the sound is transmitted with good efficiency. As shown in Figure 1, the first range might cover frequencies from 600 to 1200, the second range from 1200 to 2300 and the third range from 2300 to 4200 and so forth.

In Figure 2 I have illustrated in diagrammatic fashion how a sound transmitting system of this character may be arranged in practice. While I have shown in this figure only three devices each at the sound receiving and sound transmitting side of the system as an example, I do not wish to be understood to limit myself to a specific number of individual devices, since their number would obviously be determined through the purpose and result to be obtained.

Referring now to Figure 2, 1, 2 and 3 each represent a sound receiver for instance a microphone which is connected electrically to the main transmission line l_1 , l_2 through individual circuits to be referred to herein-after more specifically. Each microphone is suitably tuned acoustically to a certain range of tone frequencies different from the range to which the other microphones are tuned, and in such manner that by the total number of microphones employed the entire range of tone frequencies is included which it is desired to cover. Thus each microphone may easily be designed to operate at the best possible efficiency within its own small range. Of course, instead of a microphone, any other suitable sound receiver may be used as an equivalent.

As stated before, each microphone is connected to the main line l_1 , l_2 by means of an individual circuit connection. The microphones may be energized from a common circuit, containing the direct current source 11—for instance a battery—bridged by a condenser 10. For each microphone a transformer 1^a , 2^a , 3^a respectively is provided, whose secondary coil is connected to an individual transmitting circuit by which it is connected to the common main line. I propose, in addition to acoustically tuning each microphone to the desired individual range of frequencies, to also electrically dimension the above mentioned individual circuit connection between the microphone and the main line to its particular range of frequencies. This electric dimensioning may comprise any suitable expedient well known in the art, such as so-called "filter circuits" which for instance readily permit the passage of currents within a definite range of frequencies, but which offer high impedance to currents of all other frequencies outside of the range for which they are designed, or also such as simple "tuned circuits." Thus, for instance the microphone 1 (which may cover the lower frequencies) may be connected to the main l_1 , l_2 through its transformer 1^a and a circuit containing a number of filter circuits having the inductances 4 and 5 and the capacities 6

and 7, arranged as shown, whereas microphone 2 (middle frequency range) may be connected to the main line through simple tuned circuits having the inductance 8 and 5 the capacity 9 arranged as shown. Microphone 3 (highest range) may be connected to the main line in a fashion similar to the connection of microphone 1, but in this case the capacities 14, 15 are connected in series and 10 the inductances 12, 13 are connected in shunt, in order to suppress the lower frequencies in this circuit.

The sound transmitting or radiating end which may represent a loud speaker may be 15 arranged as follows:—

Three telephones 16, 17 and 18 are arranged around a common tone chamber 19. The diaphragms of these telephones are indicated at 20 and their energizing coils are denoted by 20 21. Each telephone is provided with a specific individual tone chamber 22 and each telephone diaphragm 20 with its pertaining tone chamber 22 is tuned to a certain frequency different from the frequencies to 25 30 which the other diaphragms and pertaining chambers are tuned, so that for instance in this case for each telephone an acoustically coupled system is produced (consisting of a diaphragm and a tone chamber) which covers a range of frequencies such as is indicated in Figure 1. The main chamber 19 may open into a horn 23, the shape of which may also be formed suitable with relation to the main chamber 19 so as to produce the 35 best possible efficiency.

The energizing coils 21 of the individual telephones 16, 17 and 18 are connected with the main line l_1 , l_2 through circuits which may be electrically tuned individually to the 40 pertaining frequencies of the individual telephones in a manner similar or equivalent to that explained and shown with reference to the sound receiving side of the system. For this purpose condensers 24 and inductances 45 50 are arranged in these circuits for instance all in a similar fashion, although they may of course be arranged for each circuit in any other suitable manner well known in the art so as to produce the desired electrical filtering or tuning effect.

I have shown in Figure 2 the three telephones, in other words, a plurality of sound radiators, arranged so that their sound emanates through a common horn. If desired it 55 is, of course, possible to also have an individual horn for each telephone the same as at the other end of the system an independent individual microphone is shown for each range of tone frequencies. Likewise instead 60 of having a number of independently arranged microphones they all may be arranged to receive the sound from a common horn or speaking tube such as is shown at 23 at the radiating end of the system. Also, if expedient, the number of individual sound de-

vices at one end of the system, may not be equal to that at the other end of the system. These modifications are considered as being equivalents and intended to be within the scope of the present invention.

The manner of electrically transmitting the sound, after it has once been converted into oscillating electrical energy, may be entirely within the discretion of those skilled in the art, and I have, therefore, omitted in 70 the drawings a direct conductive connection between the sound receiving and sound radiating end of the system, the gap, being indicated by the letter x , denoting that the transmission may be either directly, such as by 75 direct conductors, or indirectly such as by inductive transformation or by radio transmission or the like, the mode of transmitting the oscillating electrical energy having no bearing on the operation and function of the 80 present invention. Also if desired, only one of the two ends of the system shown in Figure 2 may be used alone, that is to say, for instance the oscillating electrical energy into 85 which the sound received by the microphones 90 is transformed, may be conveyed by lines l_1 , l_2 to any device suited for receiving and utilizing such energy.

I claim:—

1. In a multiple range electric sound transmitting system a plurality of individual independent sound responsive devices actuated simultaneously and located to be responsive for the same sound waves, each being electrically and acoustically dimensioned to a 95 definite different portion of the entire range of sound frequencies to be covered, to the exclusion of all other portions of said range.

2. In a multiple range electric sound transmitting system a plurality of sound responsive devices actuated simultaneously and located to be responsive for the same sound waves, comprising independent individual sound receivers and sound radiators arranged at the two ends of the system respectively, 100 each receiver and radiator comprising a plurality of mechanically coupled oscillatory structures, the devices at each end being each electrically and acoustically dimensioned for a 105 definite different portion of the entire range of sound frequencies to be covered, each device excluding all other portions of said range and a common electrical transmitting connection between the sound receivers and radiators.

3. In a multiple range electric sound transmitting system a plurality of sound responsive devices actuated simultaneously, comprising independent individual sound receivers and sound radiators arranged at the two ends of the system respectively, each receiver and radiator comprising a plurality 115 of mechanically coupled oscillatory structures, the devices at each end being each electrically and acoustically dimensioned for a 120 125 common electrical transmitting connection between the sound receivers and radiators.

definite different portion of the entire range of sound frequencies to be covered, each device excluding all other portions of said range and a common electrical transmitting connection between the sound receivers and radiators, and means for combining the acoustical transmitting effect of the individual devices.

4. In a multiple range electric sound transmitting system a plurality of individual independent sound responsive devices actuated simultaneously and located to be responsive for the same sound waves, each being electrically and acoustically dimensioned to a 15 definite different portion of the entire range of sound frequencies to be covered, to the exclusion of all other portions of said range, the said sound responsive devices consisting of mechanical vibratory systems and electrical circuits, each of said mechanical systems comprising a plurality of mechanically coupled oscillatory structures, the individual

structures of any one system having the same natural frequency before coupling.

5. In a multiple range electric sound transmitting system a plurality of individual independent sound responsive devices actuated simultaneously and located to be responsive for the same sound waves, each being electrically and acoustically dimensioned to a 20 definite different portion of the entire range of sound frequencies to be covered, to the exclusion of all other portions of said range, the said sound responsive devices consisting of mechanical vibratory systems and electrical circuits, each of said mechanical systems comprising a plurality of mechanically coupled oscillatory structures, the individual 25 structures of any one system having the same natural frequency before coupling, and the 30 said electrical circuits consisting of filter circuits.

WALTER HAHNEMANN.
